UNITED STATES PATENT OFFICE.

CHARLES EDWARD MAY, OF DUNEDIN, NEW ZEALAND.

THERMOSTAT.

SPECIFICATION forming part of Letters Patent No. 643,722, dated February 20, 1900.

Application filed November 14, 1898. Serial No. 696,488. (No model.)

To all whom it may concern:

Be it known that I, CHARLES EDWARD MAY, of Dunedin, New Zealand, have invented certain new and useful Improvements in Thermostats, of which the following is a specification.

This invention relates to thermostats for detecting the presence of fire in a building and completing an electric circuit when the building becomes unduly heated for the purpose of operating an alarm.

The drawing shows a front view of the thermostat.

B is a metallic wire, which is stretched between two supports N, one of which is preferably provided with some approved means, such as a screw n, for adjusting the tension of the wire to a prearranged degree of heat, which is not to be exceeded without giving an alarm.

D is a movable contact-piece suspended from the wire B between the supports N and descending by gravity when the wire is heated.

E is a stationary contact-piece arranged in the downward path of the movable contact-piece. The stationary contact-piece may be

set or adjusted vertically in any approved manner, and it preferably consists of a cup partially filled with mercury.

A are the line-wires of a battery K, and I is an annunciator included in the circuit. One wire A is connected to one of the supports N, and the other wire A is connected to the contact-piece E.

When a fire occurs in a building supplied with one or more of these devices and the heat is so great as to cause the movable contact-piece to complete the circuit, an alarm is sounded.

What I claim is—

The combination, with a metallic wire, and means for stretching it; of a movable contact-piece suspended from the wire between its ends and descending by gravity when the wire is heated, and a stationary contact-piece arranged in the downward path of the movable contact-piece, substantially as set forth.

Dated this 4th day of August, 1898.

CHARLES EDWARD MAY.
